RUDDER

John Livingston, Pelham Manor, N. Y.

Application July 9, 1943, Serial No. 493,985

12 Claims. (Cl. 114—162)

This invention relates to ships' rudders, and more particularly, though not exclusively, to rudders of the type sometimes called "fishtail" rudders, in which upper and lower streamlined sections, above and below the propeller axis and aft of the pivotal axis, are substantially symmetrical with the fore-and-aft rudder axis at top and bottom respectively but flare divergently rearward and from top and bottom to a maximum at the median horizontal plane in line with the propeller axis. A rudder of this general type, in the form of a balanced rudder, is shown and described in my U. S. application for patent, Serial No. 412,533, filed September 27, 1941, Patent No. 2,331,706, of which the present application is a continuation in part. The construction forming the subject matter of my present application for patent is in most respects better suited for pivotal mounting substantially at its leading edge and aft of guide vanes fixedly mounted at the stern of the ship.

Important objects of the invention are to provide a rudder construction of great strength, while being of comparatively light weight and low cost and capable of being rapidly produced. At the same time, the construction embodies features which render the rudder easy of access for repairs, and one which involves comparatively low maintenance cost.

The invention will be described in detail with reference to the details of construction shown in the accompanying drawings, in which—

Figure 1 is a rear elevational view of the rudder per se before mounting upon the stern frame of a ship.

Figure 2 is a side elevational view of the rudder per se, with one of the side plates removed.

Figures 3, 4 and 5 are enlarged horizontal sectional views taken respectively on the lines 3—3, 4—4 and 5—5 of Figure 2.

Figure 6 is an enlarged fragmentary vertical sectional view taken through the pivotal connection between the rudder and the stern frame of a ship.

Figures 7 and 8 are detail horizontal sectional views taken on the respective lines 7—7 and 8—8 of Figure 6.

Figure 9 is a side elevational view with parts broken away in vertical section of a modified form of the invention showing a rudder pivotally mounted to the stern frame of a ship.

Figure 10 is a slightly enlarged horizontal sectional view taken on the line 10—10 of Figure 9.

Figure 11 is a detail vertical sectional view on the line 11—11 of Figure 9.

Referring to the drawings by reference characters, the numeral 1 designates in its entirety a rudder which is constructed largely of welded sheet metal in the manner set forth in my aforesaid application, Serial No. 412,533. The rudder

shown by way of example is of the "fishtail" type and designed for use with a right-handed propeller. It comprises a hollow upper body 2 and a hollow lower body 3, which bodies meet at the plane of the propeller axis of the ship on which the rudder is to be pivotally mounted. The upper and lower rudder bodies 2 and 3 are of streamline shape in cross section and have rounded leading edges 4 which are disposed in the same vertical plane. The pivotal axis of the rudder bodies 2 and 3 is designated A—A. At the top of the upper rudder body 2 and at the bottom of the lower rudder body 3, the contour of the rudder is symmetrical, or nearly so, to the longitudinal vertical median plane, while the bottom of the upper rudder body 2 and the top of the lower rudder body 3 flare divergently from this median plane. The trailing surfaces 5 and 6 of the upper rudder body meet to form a trailing edge 8 which curves downward and outward to starboard from said median plane. The trailing surfaces 9 and 10 of the lower rudder body 3 meet to form a trailing edge 11 which curves upward and outward to a point offset to port from the median plane. The trailing surfaces are thus warped oppositely or divergently from the longitudinal vertical median plane of the rudder, and their proximate portions are offset from each other by the sum of their divergencies from this median plane. A web 12 joins and extends between these relatively offset portions, to segregate the upper and lower portions of the propeller stream.

Structurally, the rudder 1 includes a lower rudder stock in the form of a length of steel pipe or tube 13 of a diameter which predetermines the thickness of the leading edge 4, and which is of a length shorter than the height of the rudder to provide shouldered or stepped corners B and C respectively, adjacent the top and bottom of the rudder at its leading edge. The pivotal axis A—A extends through the axis of the tube 13. Each hollow rudder body 2 and 3 includes suitably-shaped opposed sheet metal side plates 14—14 which have their front edges welded to opposed sides of the tube 13 as at 15—15, the rear edges thereof being, for example, welded at 16 to a flat metal bar 17 to form the trailing edges 8 and 11. The top of the upper rudder body 2 is closed by a top plate 18, and the bottom of the lower rudder body is closed by a bottom plate 19, said top and bottom plates being welded to the side plates 14—14 of the respective rudder bodies. A shelf plate 20, which is a continuation of the aforesaid web 12, closes the bottom of the upper rudder body 2 and the top of the lower rudder body 3, said shelf plate being welded to the side plates 14—14 having its front end shaped to conform with the tube 13 to which it is also welded. Diaphragm plates 21 disposed

in spaced relation within the hollow rudder bodies are welded to the side plates and to the tube 13 and cooperate with a vertical transverse metal diaphragm 22 and metal flanges 23 to transmit the torque and rigidly reinforce the side plates against collapse.

Fixedly mounted to the rudder 1 at the top and bottom corner shoulders B and C are corner fittings 24 and 25 respectively. The top fitting 24 is cast in one piece and includes an inverted L-shaped body 26 having a vertical web 27 and an integral horizontal flange 28, which portions are further connected by a diagonal central web 29. The top front ends of the side plates 14-14 of the upper rudder body 2 overlap the web 27 and are welded thereto as at 29a, as best illustrated in Figure 7. The flange 28 is shouldered as at 30 to provide a ledge surface for the top plate 18 and to which the top plate is welded as at 31. Integral with the web 27 and extending forwardly therefrom is a gudgeon 32 and a spaced vertically-aligned flange 33. The flange 33 is at the lower end of the web 27 and is provided with an annular collar 34. The collar 34 is concentric to the pivotal axis A-A and of a diameter to snugly fit into the top of the tube 13 to which it is secured by welding 35. The flange 33 is provided with an aperture 36 which admits a boring bar during manufacture and is closed by welding a thin metal plate 37 to the top face of the flange 33.

The gudgeon 32 is provided with a bore 38 which is concentric to the pivotal axis A-A in which a brass sleeve bushing 39 is mounted and which is held in place by a shoulder 40 at the lower end of the bore and by welding a retaining ring 41 on the top face of the gudgeon 32 in overlapping relation to the top end of the sleeve bushing. The retaining ring 41 is not applied until after the rudder has been positioned relative to the stern frame F of the ship, and which stern frame is fragmentarily shown in the drawings. The stern frame F includes a gudgeon 42 having a downwardly-tapered bore 43 which is concentrically aligned with the bore 38. A pintle 44 hingedly connects the corner fitting 24 with the gudgeon 42 of the stern frame, said pintle having a uniform cylindrical upper portion 45, a downwardly-tapering intermediate portion 46, and a reduced lower threaded shank portion 47. The upper portion 45 is enclosed by a brass cap bushing 48 which is disposed in the bushing 39. The lower end of the bushing 48 extends below the gudgeon 32, and fitting thereagainst is a rubber gasket 49 which encircles the pintle 44. The upper face of the gudgeon 42 is recessed to accommodate the gasket 49 and lower end of the bushing 39. The tapered portion 46 of the pintle is seated in the tapered bore 43 of the gudgeon 42 with the threaded shank 47 extending below the plane of the under face of the gudgeon. A nut 50 is threaded to the shank 47 and is held against backing off by a cotter pin 51 which passes transversely through the shank. The space in which the nut 50 is disposed is enclosed by a substantially horseshoe-shaped metal plate 52 which has its rounded portion concentric to the pivotal axis A-A. The lower edge of the plate 52 rests upon a shouldered ledge 53 of the flange 33 to which it is welded as at 54. The ends of the plate 52 seat against the shouldered portions 55 provided at the sides of the web 27 where they are welded as at 56.

The lower corner fitting 25 includes a vertical web 57 having an upper forwardly-extending

flange 58 and a lower gudgeon 59. The top face of the upper flange 58 is provided with a vertical annular flange 60 concentric to the pivotal axis A-A and of a diameter to snugly enter the lower end of the tube 13 to which it is welded as at 61. The flange 58 is provided with a boring bar aperture 62 which is closed by welding a disk plate 63 to the under face of the flange 58. The sealing of the apertures 36 and 62 by welding plates thereover, and the welding of the top and bottom ends of the tube 13 to the aligned confronting flanges 33 and 58, provide water-tight joints for preventing the entrance of water into the tube 13. The lower gudgeon 59 is provided with an upwardly-tapered bore 63 which is concentric to the pivotal axis A-A. Extending beneath the gudgeon 59 is the rearwardly-extending shoe 64 of the stern frame F. The shoe 64 is provided with a cylindrical bore 65 which is concentric to the pivotal axis A-A and which is lined with a brass sleeve bushing 66 held in place by a retaining ring 67 welded to the upper wall of a recess 68 provided in the underside of the shoe 64. Fitted into the bushing 66 is the lower cylindrical portion 69 of a pintle 70, said portion being enclosed in a cap bushing 71. The pintle 70 further includes an upwardly-tapered intermediate portion 72 which seats in the tapered bore 63, and a reduced threaded shank portion 73 which extends beyond the top of the gudgeon 59 and receives a nut 74. A cotter pin 75 passes transversely through the threaded shank 73 to prevent accidental backing off of the nut from the threaded shank. The space between the flange 58 and gudgeon 59 is sealed by a substantially horseshoe-shaped plate 52', the bottom edge of which rests upon and is welded at 54a to the upper face of the gudgeon 59, while the top edge thereof is seated against a shouldered surface on the flange 58 and welded thereto as at 54b. The ends of the plate 52' are welded at 56a to the body 57 of the fitting 25. The plate 52' seals the space within which the nut 74 is disposed. The upper end of the bushing 71 extends into a recess in the underside of the gudgeon 59. A rubber gasket 76 is also disposed in the aforementioned recess in sealing engagement with the walls thereof and with the pintle 70 and upper end of the bushing 71.

The underside of the fitting 25 is provided with a shouldered surface 77 to receive the front end of the bottom plate 19 to which the plate is welded as at 78. The side plates 14-14 of the lower rudder body 3 are welded at 29a to the shouldered surface provided on the sides of the body 57 of the fitting 25. The welding of the plates of the rudder at their joinder with shouldered surfaces of the fittings 24 and 25 provides water-tight joints to prevent water from entering the hollow rudder bodies 2 and 3.

The flange 28 of the upper corner fitting 24 extends beyond the plane of the sides of the upper rudder body 2, and bolted to such extending portion as at 79 is the flanged lower end or rudder coupling 80 of the upper rudder stock 81.

When shipping the rudder 1 on the stern frame F, the pintle 70 is first inserted into the tapered bore 63 of the lower corner fitting 25 and clamped thereto by the nut 74. The pintle 70 is next inserted into the bearing bore 65 of the shoe 64, and the gudgeon 32 is aligned with and over the gudgeon 42 of the stern frame. Next, the pintle 43 is inserted down through the gudgeon 32 with the tapered portion 46 seated

in the tapered bore 43 of the gudgeon 42. The nut 50 is applied to the threaded shank of the pintle 43, thus clamping the pintle and gudgeon together. The upper cylindrical portion 45 of the pintle 43 is disposed in the cylindrical bore 38 of the gudgeon 32. The rudder is now hingedly supported upon the stern frame. To complete the mounting operation, it remains only to weld the horseshoe-shaped plates 52 and 52' in position to house the nuts 50 and 74 and to close the space between the flanges 33 and 58 and the respective gudgeons 42 and 59.

From the foregoing description, it will be apparent that the rudder 1 will freely swing upon the pivotal axis A—A which passes through the vertically-aligned pintles 44 and 70. Also, the corner fittings although relatively light in weight are sufficiently strong to withstand the stresses imparted thereto during use, and they cooperate with the tubular rudder stock to effect a continuous reinforcement along the entire height of the leading edge of the rudder. The gudgeon and pivotal mountings are of such construction as to enable the rapid shipping of the rudder and its subsequent unshipping for repair or replacement purposes.

In Figures 9 to 11 inclusive, there is illustrated a modified form of the corner fittings. In the previous construction hereinbefore described, the corner fittings 24 and 25 are cast in one piece, but each may be formed as a weldment in a manner now to be described.

Reference characters heretofore used to designate the various parts of the invention are employed in Figures 9 to 11 inclusive, to indicate corresponding parts.

The upper and lower corner fittings in Figures 9 to 11 inclusive are designated in their respective entirieties by the reference characters 24a and 25a. The upper fitting 24a has a right-angle flange section 28a. The horizontal portion of the flange section 28a has the flange 80 of the upper rudder stock 81 bolted thereto as at 79. A gudgeon 32a has its top face welded at 82 to the vertical portion of the section 28a, while the under face of the gudgeon 32a is welded at 83 to the top of the vertical web of an L-shaped section 27a. The section 27a includes a flange 33a to which the upper end of the tube 13 is welded. A central web 29a is welded to the inner side of the sections 28a as at 84.

The corner fitting 25a comprises a lower flange 59a to the top face of which is welded, at 85, the bottom of an inverted L-shaped section 57a. The section 57a includes flange 58a which corresponds to the flange 58 to underlie and close the bottom end of the tube 13.

The corner fittings 24a and 25a differ from the fittings 24 and 25 only in the fact that they are constructed as weldments. The functions of the fittings 24a and 25a are the same as the fittings 24 and 25, respectively, so that a further explanation thereof is not believed necessary.

In my patent hereinbefore referred to, the rudder proper has leading surfaces shaped to offer minimum resistance to the propeller stream. Figures 9 and 11 embody this same principle in a somewhat different form; instead of being embodied in the rudder, it is embodied in guide vanes mounted rigidly on the stern frame F forward of the leading edge 4 of the rudder 1. The guide vane structure is designated 90 in its entirety and includes an upper guide vane section 91 and a lower guide vane section 92, which meet on the 75

same horizontal plane as the web 12 which connects the upper and lower rudder bodies 2 and 3 already described. The guide vane sections 91 and 92 are similar in construction, but their cross-sectional contours are reversely arranged to conform with the propeller stream above and below the horizontal axis of the ship's propeller, and to guide the streams to the respective upper and lower rudder bodies 2 and 3 of the rudder. The guide vane 90 has its lower end welded to the upper surface 93 of the shoe 64 of the stern frame F, while the top of the guide vane is welded to an overhanging portion 94 formed on the frame F adjacent the gudgeon 42. Each of the guide vane sections 91 and 92 includes a leading edge defined by a pipe 95 which is offset to one side of the pivotal axis A—A of the rudder 1. The pipe 95 of the upper guide vane 91 is disposed in offset position to port and the pipe 95 of the lower guide vane is offset to starboard, as best illustrated in Figure 10. Rearwardly-diverging side plates 96 and 97 have their front edges welded to the pipe 95 while their rear edges terminate forward of the sides of tube 13 of the rudder to approximate a continuation of the streamlining of the rudder. The plates 96 and 97 are held in rigid spaced-apart relation by spaced horizontal diaphragm plates 98, which conform to the cross-sectional shape of the vane section and are welded to the side plates thereof. The vane section is further braced by vertical diaphragm plates 99 which are disposed adjacent the rear edges of the side plates 96 and 97 to which they too are welded. A segregating web 100 joins the upper and lower guide vane sections 91 and 92 and is in alignment with the propeller axis of the ship. It is understood that the part of the propeller stream striking the leading edge of the guide vane just above the propeller axis has a decided inclination to starboard, while the part of the propeller stream striking the leading edge just below the propeller axis is correspondingly inclined to port. These two adjacent parts of the propeller stream, therefore, have crossing directions of flow which would result in considerable turbulence if they were allowed to pass in contact with each other. The web 100 prevents such contact of the two parts of the propeller stream and allows them to flow smoothly past each other along their respective paths, and guides them past the respective upper and lower bodies 2 and 3 of the rudder 1.

The particular arrangement of the pintles with respect to the pintle gudgeons of the rudder and the stern frame of the ship may, of course, be varied without departing from the principles of the invention. Thus, instead of having the tapered end of the upper pintle seated in the upper pintle gudgeon of the stern frame and bearing freely in the upper pintle gudgeon of the rudder, it is entirely feasible to reverse this relationship. Similarly, the seating and bearing of the lower pintle may be reversed. It is, therefore, to be understood that the invention is not limited to the particular arrangement illustrated and described for purposes of illustration.

I claim:

1. A ship's rudder having upper and lower corner fittings fixedly mounted therein, and a tubular lower rudder stock extending between said corner fittings, said corner fittings being connected in torque-transmitting relation to the respective ends of said rudder stock and having pintle-gudgeon portions in axial alignment with each other.

2. A ship's rudder having along its leading

edge a tubular lower rudder stock of a length less than the height of the rudder with its ends terminating short of the top and bottom of the rudder, and upper and lower corner fittings welded on the respective ends of said rudder stock at the top and bottom leading corners of the rudder, said corner fittings having pintle-gudgeon portions disposed in axial alinement with said rudder stock.

3. A ship's rudder having stepped top and bottom corners at its leading edge, a tubular lower rudder stock extending along the leading edge of the rudder having its ends terminating adjacent the respective stepped corners, upper and lower corner fittings fixedly secured in the said top and bottom stepped corners and provided with axially-alined pintle-gudgeon portions and rudder stock engaging flange portions in torque-transmitting engagement with the respective top and bottom ends of the said rudder stock.

4. A ship's rudder as set forth in claim 3, in which the upper corner fitting is provided with a flat horizontal rudder coupling flange extending laterally beyond the sides of the rudder, and an upper rudder stock having a rudder coupling base seated on and bolted to said rudder coupling flange for fixedly securing the upper rudder stock to the rudder.

5. A ship's rudder as set forth in claim 3, in which the stock-engaging flanges have annular shoulders seated in and welded to the ends of the tubular rudder stock.

6. A ship's rudder having a tubular lower rudder stock constituting the leading edge thereof and having its upper and lower ends terminating short of the top and bottom of the rudder respectively, an upper corner fitting in the top leading corner of the rudder, having a stock-engaging flange overlying and welded to the upper end of said rudder stock and a pintle-gudgeon flange disposed in spaced relation above said stock-engaging flange and formed with a pintle gudgeon in axial alinement with the axis of said rudder stock; and a lower corner fitting in the bottom leading corner of the rudder, having a stock-engaging flange underlying and welded to the lower end of said rudder stock and a lower pintle-gudgeon flange disposed in spaced relation beneath said stock-engaging flange and having a pintle gudgeon in axial alinement with the axis of said rudder stock.

7. In combination, a ship's stern frame having an upper pintle gudgeon and a lower pintle gudgeon, a ship's rudder having a tubular lower rudder stock along its leading edge, said rudder stock terminating short of the respective top and bottom planes of the rudder, an upper corner fitting fixedly secured to the top leading corner of the rudder, said fitting including a stock-engaging flange overlying and fixedly secured to the top of the said rudder stock, an upper pintle-gudgeon flange disposed in spaced relation above said stock-engaging flange, to provide an upper pintle gudgeon in axial alinement with the axis of the said rudder stock, a lower corner fitting including a stock-engaging flange fitting against the bottom of said rudder stock and fixedly secured thereto, a lower pintle-gudgeon flange disposed in spaced relation beneath said stock-engaging flange to provide a lower pintle gudgeon in axial alinement with the axis of said rudder stock, and upper and lower pintles disposed in the upper and lower pintle gudgeons of the stern frame and in the pintle gudgeons of said upper and

lower corner fittings to axially align said stern-frame gudgeons and said rudder stock.

8. In combination, a ship's stern frame having upper and lower pintle gudgeons, a ship's rudder having a tubular lower rudder stock along its leading edge, the ends of the rudder stock terminating short of the respective planes of the top and bottom edges of the rudder, upper and lower corner fittings fixedly secured to the rudder at the respective top and bottom leading corner edges of the rudder, means on said upper and lower fittings in torque-transmitting engagement with the top and bottom ends of said rudder stock, and upper and lower hinge-pintle means respectively connecting the upper corner fitting to said upper pintle gudgeon and the lower corner fitting to said lower pintle gudgeon, said hinge-pintle means being in axial alinement with the axis of said rudder stock.

9. In combination, a ship's stern frame, and a ship's rudder having a tubular rudder stock along its forward edge, and upper and lower corner fittings rigidly secured to said rudder stock and providing hinge-pintle connections with said stern frame disposed above and below the upper and lower ends of the rudder stock, the axes of the pintle connections being in axial alinement with the axis of said rudder stock.

10. In combination, a ship's stern frame, a rudder having its leading edge hinged at its top and bottom to said stern frame, said rudder comprising upper and lower rudder bodies joined together at approximately the plane of the propeller axis, and gradually offset with respect to each other in the direction of their trailing edges, a guide vane mounted in the stern frame forward of and closely adjacent the leading edge of the rudder, said guide vane composed of upper and lower guide-vane sections which meet at approximately the plane of the propeller axis, each of said guide-vane sections including side plates forwardly converging to a leading edge disposed in offset relation to the leading edge of the rudder, the cross-sectional contour of the upper and lower guide-vane sections being reversed relative to each other, and a segregating web connecting the offset portions of the upper and lower guide-vane sections.

11. A ship's rudder construction comprising in combination side plates forming a streamline rudder body, a tubular rudder stock within said rudder body shorter in length than the height of said rudder body, corner fittings secured to the top and bottom of said tubular rudder stock, and horizontal diaphragm plates welded at spaced intervals to said tubular rudder stock and abutting the inner surface of and welded to said side plates along lines conforming to the contours of the rudder body at their respective levels, said corner fittings provided with means for pivotal attachment of the rudder to the ship.

12. A ship's rudder of unbalanced type comprising upper and lower trailing surfaces oppositely warped and transversely offset from the longitudinal, median, vertical plane of the rudder above and below the horizontal plane of the propeller axis, the after edges of the upper and lower trailing surfaces being substantially spaced apart transversely from each other in the vicinity of the horizontal plane of the propeller axis, and a segregating web joining and extending between the offset portions and the spaced-apart after edges of said trailing surfaces.

JOHN LIVINGSTON.
